INTERNAL COMBUSTION ENGINE

Jean A. H. Barkeij, Altadena, Calif.

Application May 9, 1939, Serial No. 272,559½

12 Claims.

(Cl. 123—56)

The present application is a continuation in part of my application No. 57,001 of Dec. 31, 1935, and of my application No. 688,039½ of Sept. 2, 1933.

These two prior applications contained a part and continued a part of my Patent No. 1,911,874, Re. 21,177, Aug. 22, 1939.

In this prior patent a relatively small angle was preferred for the 6, 8, 12 cylinder type, but some of the claims thereof did not include any angle at all.

In the eight cylinder type, the crankpins of the cylinders of one group were arranged at an angle of 90° and the crankpins of the other group likewise at 90°, and said two groups of crankpins radially arranged at the angle of the two cylinder groups (the two groups of cylinders being in staggered relation).

In the present application I apply the same arrangement on the so-called opposed type, or 180° wide V-type engine, with the result that for the six cylinder type the six crankpins remain arranged in 6 radial planes, and for the eight cylinder type in only four radial planes.

If two radial planes, at 180° angle, are considered as one radial plane, there are respectively for these two types only 3 and 2 radial planes, in which the crankpins are arranged. The claims are formulated according to this last view point.

In the present application therefore this same fundamental arrangement is retained, but the offset of the crankshaft is from both cylinder planes. In the prior patent Re. 21,177, the crankshaft is offset only from one cylinder group, but in the present application the crankshaft is offset an equal amount from both groups.

In the present application I offset the cylinders an equal amount from the crankshaft axis, but in opposite direction, obtaining thereby the advantage that in any two, four, or 8, or 12 cylinder engine, the stroke of all the pistons remains the same and the balance of the reciprocating parts is not affected thereby when the engine is running. In fact the running balance is improved thereby.

In Fig. 1 I show a vertical cross section of the general type of opposed cylinders, and show a crankshaft of which two crankpins are arranged at 180°.

In Figs. 2, 4, 6, 8, 10, I have shown various crankpin arrangements which can be combined with the fundamental arrangement of the construction in Fig. 1, and in Figs. 3, 5, 7, 9, 11, I have shown the corresponding cylinder-arrangements

therefor to decrease the unbalance to a minimum, or to eliminate it entirely.

In Fig. 12, I have shown a crank pin arrangement which can be used to advantage with a four cylinder two stroke type of engine having four cylinders and Fig. 13 represents again diagrammatically the cylinder arrangement therefor.

My general object is to arrange the planes of two cylinder blocks offset from the axis of the crankshaft an equal amount, and in such a way that the connecting rods approach the axes of said cylinders on that side of the cylinders where the crankshaft is offset therefrom, as shown in Fig. 1.

Or in other words the crankshaft axis is offset from the two planes of the two cylinder blocks an equal amount on that side on which the connecting rods approach said cylinder planes, on the compression stroke.

My second general object is to arrange the crankpins in such engines in such a way that the firing takes place in accordance with the fact that two pistons, one in each block reach top position simultaneously.

My third general object is to arrange the crankpins so that the pistons in pairs of cylinders, opposed to each other, do not reach top position simultaneously (see for instance Figs. 6 and 7, in which pistons 1 and 3, 8 and 6, 4 and 2, 5 and 7 reach top position simultaneously). This object has been already explained in my previous Patent No. 1,911,874 of May 30, 1933, reissued as Patent No. 21,177 of Aug. 22, 1939, and as claimed in claim 6 of either of said patents. This object is present in Figs. 2 and 3, and Figs. 12 and 13 also, and other combinations. My fourth general object is to arrange the cylinders in each block so that they are alternately staggered with respect to each other from one end of the engine to the other end thereof. This arrangement of Fig. 5 may be combined with any of the crankpin arrangements shown in Figs. 2, 4, 6, 8, 10 and 12. This variation is combined with the first general object, and is represented in Figs. 4 and 5, in combination with Fig. 1. Another general object is to arrange the cylinders in one block different from those in the other block, by preference so that the vertical planes through the axes of the outermost cylinders of one block fall inside the vertical planes through the axes of the outermost cylinders of the other block. This variation is represented in Figs. 1 and 2, 6 and 7, 8 and 9, 10 and 11, 12 and 13, but not in Fig. 5. Other objects will appear during the description of the figures.

Referring more specifically to the Fig. 1, the cylinder 1 is arranged in the plane A—A, and the cylinder 2 in the plane B—B.

The crankshaft axis is not placed in either plane A—A or B—B but in a plane exactly midway the said two planes, the plane C—C.

The crankpins 1 and 2 on the crankshaft are arranged at 180°. In the position in which the crankpins are drawn, a single plane E—E is extended through the piston-pin-axis 1A of piston 1A—A, through the crankshaft axis C, and through the piston-pin-axis 2B of piston 2B—B. This plane E—E makes exactly the same angle alpha with plane A—A as with plane B—B.

Therefore the two pistons reach their top dead center simultaneously in the two planes A—A and B—B, and they reach that position with equal intervals of 360°.

Therefore this arrangement can be conveniently used for the two-stroke or four-stroke-cycle type.

If we apply the fundamental arrangement on a four cylinder opposed type, it is preferred to arrange the cylinders as shown in Fig. 3 diagrammatically, and the crankpins as shown in Fig. 2. That way the two sets of pistons of cylinders 1 and 3 are counterbalanced by the pistons 2 and 4. Each pair of pistons not being aligned cause a couple in a horizontal plane, proportional to the distance of the axes of the two cylinders. To counteract this couple the cylinders and crankpins should be arranged as shown in Figs. 2 and 3.

For an 8 cylinder opposed type this problem becomes slightly more complicated. If we arrange the two groups of four cylinders alternately in staggered relation, as shown in Fig. 5, we obtain the advantage that the cylinders of one block are located exactly in the same way as those in the other block, and these blocks can be bored with the same set of multiple drills, well known in the art. If we arrange the cylinders as shown in Figs. 3, 7, 9, 11, one block is substantially different from the other. However in the types of Fig. 9, the cylinders 1 and 3, 2 and 4, 5 and 7, 6 and 8, could be drilled in pairs of two individual adjacent cylinders. And in the type of Fig. 11 they could be drilled in sets of three adjacent cylinders, of which the axes are at an equal distance from each other. The crankshafts in the types of Figs. 3 and 6 are comparatively cheap to make, and those of the types of Figs. 4, 5 and 8, 9 are more expensive.

If we prefer another arrangement, that shown in Figs. 8 and 9 would be satisfactory too. The pistons in cylinders 1, 2, 7, 8 would balance each other and those in cylinders 3, 4, 5, 6.

For the twelve cylinder the most preferable arrangement would be to arrange the crankpins in aligned pairs at 120° as shown in Fig. 10 and to arrange the cylinders as shown in Fig. 11. The six sets of two pistons respectively in cylinders 1 and 6, 7 and 12, 2 and 5, 8 and 11, 3 and 4, 9 and 10 would balance each other nicely.

In fact a perfect balance is here obtained.

For the four cylinder two stroke cycle type, the arrangement of crankpins and cylinders shown in Figs. 12 and 13 would be satisfactory because the cylinders 1 and 3 could fire with 90° interval and then the cylinders 2 and 4 with the same intervals, all intervals being 90°. However the couple created by these two sets of pistons do not entirely counterbalance each other, because they follow each other up with intervals of 90°, quite unlike the arrangement of Figs. 2 and 3, in which

they are separated from each other by 180°, operating on the four stroke cycle, or two stroke cycle. The arrangements of Figs. 4 to 11 can equally well operate on the two stroke cycle as on the four stroke cycle.

The crankshaft of Fig. 6 and Fig. 12 have this in common, that the adjacent crank pins 1 and 2, 3 and 4, 5 and 6, 7 and 8, are aligned in said pairs. In Fig. 6 the crank pins 1 and 2, 3 and 4, 5 and 6, 7 and 8 can be considered as single crank pins having two connecting rods of opposed cylinders arranged thereon, so that it may be considered as a four crank pin, 90°, crankshaft, in which crank pins 1 and 2, are arranged at 180°, and crank pins 3 and 4 at 180°, these two sets of crank pins arranged at 90°, as already shown in the Patent No. 1,285,129 of Nov. 19, 1918, to Goodrich.

The type of Fig. 12 is different. Here the crank pins 1 and 2 are at 90° and crank pins 3 and 4 are at 90°, these two sets arranged so that crank pins 2 and 3 are at 180°, and crank pins 1 and 4 are at 180°. This type has been explained by me in my Patents No. 2,012,902 of Aug. 27, 1935, and No. 2,127,079 of Aug. 18, 1938, in connection with a system of gas distribution.

It is understood, that the crank pin arrangements Fig. 6 and Fig. 12 may be combined with the cylinder arrangement of Fig. 5. In the combination of Figs. 6 and 5, the pistons in cylinders 1 and 3, 8 and 6, 4 and 2, 5 and 7 reach their top position simultaneously. In the combination of Fig. 5 with Fig. 12, the pistons in cylinders 1 and 8, 3 and 6, 7 and 2, 5 and 4. In each of said cases the two pistons reaching top position simultaneously, one in each cylinder block, are in non-opposite cylinders.

As explained in my prior Patent No. 1,911,874, the two sets of crankpins for the eight and the six cylinder are arranged at the cylinder angle, which is 180°, so that the crankpins of non-opposite, or of opposite cylinders, are placed always at 180°. The cylinders 1 and 2, 3 and 4, 5 and 6, 7 and 8, in Fig. 5, are called opposite cylinders; and cylinders 1, 3, 5, 7 are arranged staggered with relation to the other cylinders 2, 4, 6, 8 in the same direction alternatively.

The difference between the six cylinder type and eight cylinder type is fundamental. In a three cylinder engine in line, having a crankshaft with three crankpins at 120°, the primary and secondary inertia forces are balanced or substantially balanced, but in a four cylinder in line engine, having four crankpins at 90°, this engine is substantially unbalanced as to couples of primary inertia forces and secondary inertia forces.

For the six cylinder therefore, the cylinder angle affects the total balance little, but in the eight cylinder engine, the angle of the two cylinder groups affects the balance greatly.

For instance, if we place the crankshaft of Fig. 12 (in which the crankpin 1 in fact represents the crankpins 1 and 2 in aligned formation, crankpin 2 the crankpins 3 and 4, crankpin 2 the crankpins 5 and 6, and crankpin 4 the crankpins 7 and 8) in an engine having eight cylinders in 2 cylinder groups at 90°, we obtain a perfect balance of the primary and secondary inertia forces, and the couples left therein, if we stagger the cylinders as shown in Fig. 5, is relatively small. At any other angle, this engine is unbalanced.

In the 180° eight cylinder type, we cannot obtain a perfect balance in any type, but some are considerably better than others, and in some we can obtain a much more favorable firing order

with respect to explosion pressure on intermediate bearings than in others. And the direction of firing in certain types is far better than in others.

For that reason the six cylinder type is fundamentally different from the eight cylinder type, and claims to these different types should be differentiated.

In the Figs. 2 to 11, the crankpins are arranged in one quarter as many radial planes as there are cylinders, for the four cylinder one plane, for the eight cylinder two planes, for the 12 cylinder three planes, etc.

In the Figures 12 and 13, however, the crankpins are arranged in one half as many radial planes as there are cylinders.

I claim:

1. In an internal combustion engine having four cylinders arranged in two planes around the crankshaft alternately in staggered relation, said crankshaft having only two crankpins, the connecting rods of the pistons of the cylinders 1 and 2 being arranged side by side on one crankpin, and the connecting rods of the pistons of cylinders 3 and 4 arranged side by side on the other crankpin, said crankpins so arranged that the pistons in cylinders 1 and 3, and those in cylinders 2 and 4 reach their top dead center position simultaneously with an interval of 180°, said two groups of cylinders arranged at 180°, the axis of said crankshaft offset an equal amount from said two cylinder planes and on that side of both cylinder planes on which the connecting rods of all pistons approach the axes of said cylinders.

2. In an eight cylinder engine, having four cylinders arranged in two planes and alternately in staggered relation, so that cylinders 1, 3, 5, 7 appear in one plane and cylinders 2, 4, 6, 8 in the other plane, cylinders 1 and 2, 3 and 4, 5 and 6, 7 and 8 being arranged substantially opposite each other, but staggered, said crankshaft having four crankpins so that the connecting rods of said latter pairs of cylinders may be arranged side by side on said respective crankpins, said crankpins so arranged that crankpins 1 and 4 are at 180°, and crankpins 2 and 3 are at 180°, said crankpins arranged at 90°, the axis of said crankshaft being offset from said two cylinder planes an equal distance and on that side of said planes on which the connecting rods approach the axes of said cylinders on the compression stroke.

3. In a multicylinder engine, having its cylinders arranged in two groups at 180°, and a minimum of two cylinders in each group, said cylinders arranged alternately in staggered relation in the same direction, a crankshaft having as many crankpins as cylinders, said crankpins arranged in pairs, so that two pistons reach their top position simultaneously, and said pairs of pistons with equal intervals, the axis of said crankshaft offset from both cylinder planes an equal amount, on the side on which the connecting rods attached to said crankpins approach the axes of said cylinders on the compression stroke.

4. In an engine, having twelve or less, but greater than four, cylinders arranged in two groups at an angle of 180°, said cylinders in staggered relation, a crankshaft having as many crankpins as there are cylinders, said crankpins arranged in one quarter as many radial planes as there are cylinders, so that two pistons in one group at the time, reach their top dead center simultaneously with equal intervals, said crankshaft being placed midway the axes of said two cylinder groups and offset therefrom an equal

amount on the side on which the connecting rods, attached to said crankpins, approach the axes of the cylinders on the compression stroke.

5. In an engine having eight or more cylinders arranged in two groups at an angle, said cylinders arranged in staggered relation, a crankshaft having as many crankpins as there are cylinders, said crankpins arranged in pairs so that two pistons in one group at the time, reach their top position simultaneously, said crankpins being so arranged that the firing sequence causes alternate firing in said two groups, the axis of said crankshaft being arranged midway the axes of the cylinder groups and offset therefrom an equal distance on the side on which the connecting rods, attached to said pistons, approach the axes of said cylinders on the compression stroke.

6. In a multicylinder engine, having four or more cylinders arranged in two groups at an angle of 180°, said cylinders in staggered relation, a crankshaft having as many crankpins as there are cylinders, said crankpins arranged in half as many planes as there are cylinders, said crankshaft being offset with its axis an equal distance from both cylinder groups, on the side on which the connecting rods, attached to said crank pins, approach the axes of the cylinders on the compression stroke.

7. In an engine of the four stroke cycle type, having eight or more cylinders in two groups at an angle of 180°, said cylinders in staggered relation, a crankshaft having as many crank pins as there are cylinders, said crankpins arranged in one quarter as many radial planes as there are cylinders, said crank pins arranged in pairs, so that two pistons, one in each group, reach their top position simultaneously in non-opposite cylinders, the firing being non-alternative between the two groups, said crankshaft being offset with its axis an equal distance from both cylinder groups on the side on which the connecting rods, attached to said crank pins, approach the axes of the cylinders on the compression stroke.

8. In a multicylinder engine of the four stroke cycle type, having its cylinders arranged in two groups at an angle, and a minimum of two cylinders in each group, said cylinders arranged in staggered relation, a crankshaft having as many crankpins as cylinders, said crankpins arranged in pairs so that two pistons reach their top position in non-opposite cylinders simultaneously, one in each group, and said pairs with equal intervals, the axis of said crankshaft offset from both cylinder planes an equal amount on the side on which the connecting rods, attached to said crank pins, approach the axes of said cylinders on the compression stroke.

9. In a multicylinder engine, having its cylinders arranged in two groups at an angle, and a minimum of four cylinders in each group, said cylinders arranged alternately in staggered relation in the same direction, a crankshaft having as many crank pins as cylinders, said crank pins arranged in pairs so that two pistons reach their top position simultaneously, one in each group, and said pairs of pistons with equal intervals, the axis of said crankshaft offset from both cylinder planes an equal amount, on the side on which the connecting rods, attached to said crank pins, approach the axes of said cylinders on the compression stroke.

10. In a multicylinder engine, having its cylinders arranged in two groups at an angle, and a minimum of four cylinders in each group, said

cylinders in staggered relation, a crankshaft having as many crank pins as cylinders, said crank pins arranged in pairs, so that two pistons in non-opposite cylinders reach their top position simultaneously, one in each group, and said pairs of pistons with equal intervals, the axis of said crankshaft offset from both cylinder planes an equal amount on the side on which the connecting rods, attached to said crank pins, approach the axes of the cylinders on the compression stroke, and the firing being non-alternative between said two groups.

11. In a multicylinder engine, having its cylinders arranged in two groups or planes at an angle of 180°, and a minimum of two cylinders in each group, said cylinders in staggered relation, a

crankshaft having as many crankpins as there are cylinders, the crankpins of each group being arranged at 360° divided by the number of cylinders in each group, these two sets of crank pins so arranged with respect to each other that said pistons reach their top dead center with equal intervals, one at the time, so that the firing may be with equal intervals, the crank pins being arranged in half as many planes as there are cylinders.

12. The engine of claim 11, in which there are two cylinders in each group, the crank pins of one group arranged at 180° opposite each other, the crank pins of the other group similarly arranged at 180°, said two groups placed at 90°.

J. A. H. BARKEIJ.
